UNITED STATES PATENT OFFICE

ROLAND A. FURLONG, OF ROCHESTER, NEW YORK, ASSIGNOR TO THE YAWMAN & ERBE MANUFACTURING COMPANY, OF ROCHESTER, NEW YORK, A CORPORATION OF NEW YORK

VISIBLE INDEX CARD HOLDER

Application filed June 27, 1930. Serial No. 464,167.

This application has to do with improvements on the devices shown, described and claimed in an application filed by Roland A. Furlong and James R. Clark on November 5, 1928, Serial No. 317,179. It has for its principal object to provide an improved card holder which shall be of simple and inexpensive construction, easy to form in manufacture, readily manipulated by the operator in use and durable for its purpose. A further object of the invention is to incorporate, in such a card holder, means to facilitate the ready engagement and disengagement therewith of visible index cards having hinge elements.

The improvements will be made clear in connection with the embodiment shown in the accompanying drawings, wherein:

Figure 1 is a view in plan of the improved card holder.

Figure 2 is a view in end elevation thereof.

Figure 3 is a sectional view taken on the plane indicated by the line 3—3 of Figure 1 and looking in the direction of the arrows.

Figure 4 is a view in plan showing a single index card engaged with the holder illustrated in Figure 1.

Figure 5 is a sectional view on the plane indicated by the line 5—5 of Figure 4 and looking in the direction of the arrows.

Figure 6 is a sectional view similar to Figure 5 but showing a similar hinge applied to a double index card.

Figure 7 is a view similar to Figure 1.

Figure 8 is a view in plan showing two pairs of hinges engaged with different groups of cards engaged with spaced slotted restrictions in the card holder.

Figures 9 and 10 are sectional views taken on the planes indicated by the lines 9—9 and 10—10, respectively, of Figure 8 and looking in the direction of the arrows.

The improved card holder *a* in its preferred form is made from sheet aluminum or any other material of suitable strength which can be readily stamped and formed. From the blank is formed a channel *b*, in cross-section, and at spaced intervals along the length of the card holder the side walls of

the channel are drawn together to provide, in the illustrated embodiment, a restricted slotted portion *b'* adjacent one end of the card holder, and two spaced slotted restricted portions *b²* and *b³* adjacent the other end of the card holder. At the inner end of each of these slots the side walls of the channel may be drawn completely together as indicated at *b⁴* so as to provide limit stops at the ends of the slots to hold the hinges against relative movement therein as will appear more clearly hereinafter. Each of the slotted portions *b'*, *b²*, *b³*, has its open end presented towards the mid-section of the holder *a*, their limit stops serving to close their other ends, respectively. In thus forming the walls of the channel in the manner described it will be clear from Figures 2 and 3 that they are inclined and their cross-sectional form will add materially to the stiffness and strength longitudinally of the card holder. These desirable characteristics are thus accomplished in the simplest possible manner and without additional operations while the desired provision is made for mounting of the cards. The article is sturdy, light in weight, easy to produce in quantity by simple forming operations and convenient for use by the operator. If desired, to facilitate its endwise movement in the tray, notches *b⁵* adjacent its opposite ends may be cut out for engagement by the finger or a suitable tool to facilitate movement of the card holder in the tray.

The index cards which are to be mounted in the holder must carry hinge members for engagement with the slots *b'* and *b³* or any two of them of the slots *b²* or *b³*. The most suitable form of hinge is described in the said copending application and consists of a piece of fabric *c* which may be glued to the opposite side faces of a card *d* and enlarged at its fold, as by a fold *c'* therein. The restricted slots *b'*, *b²* and *b³* are less in width than the diameter of the fold *c'* on the hinge. The channeled portion *b* of the holder *a* is of sufficient length adjacent the open end of each one of the slots *b'*, *b²*, *b³* to receive the hinge elements *c*. Thus, as illustrated in Figure 4, when the hinges are to be engaged with the restricted slots, the left-hand

hinge of the card *d* will be introduced into the channel *b* adjacent the one end of the slot *b'* and then slid along the slot with the cord-enlarged fold engaged by the walls of

- 5 the holder. When the hinge element has reached the end of the slot *b'*, the card may be bent sufficiently to introduce the right-hand hinge in the open channel adjacent the open end of the slot *b*³ whereby the fold may 10 be slid along the channel under the slot until the card lies flatwise as illustrated in Figure 4.

If a folded card is used providing two sheets as indicated at *d'*, *d*², in Figure 6 the 15 hinge *c* can be glued to the outer faces thereof as previously described and the hinges will be engaged with the holder exactly as though a single card *d* were carried.

In Figures 8, 9 and 10 the cards affording 20 three sheets are illustrated as mounted in the holder. Thus, one card *e* has its hinges indicated in dotted lines at *c'*, *e*² of the Figure 8 and another double card presents two sheets *f'*, *f*² shown as having hinge members *f*², *f*³. 25 The double card *f*, *f'*, is first mounted by engaging its hinges *f*², *f*³, with the spaced slots *b'*, *b*³ as described with reference to Figure 4. The card *e* may then be mounted in the 30 holder by inserting the hinge *e'* in the open channel and sliding it into the slot *b'* alongside of the hinge *f*². The other hinge *e*² may then be engaged similarly with the slot *b*². Each of the cards may have tabs exposed to view at their lower edges as illustrated in Figure 8 for convenient selection. 35

It is to be understood from the copending application that in accordance with its disclosure, any desired number and arrangement of index card sheets within certain limits can be brought together for support by a single pair of hinged elements and thereby introduced in and withdrawn from the improved card holder *a* by the simple manipulations described, regardless of the number 40 of such sheets involved. By providing a card holder which will receive two pairs of hinges, even greater flexibility in the selection of sheets and greater capacity of the tray are obtained. 45

50 What I claim is:

1. A stiff card holder formed as an open channel having two side walls of equal height throughout their length and having the edges of the side walls of the channel brought together at intervals to form narrower slots. 55
2. A stiff card holder formed as an open channel and having the edges of the walls of the channels brought together at intervals to form narrower slots, and other edge portions in engagement contiguous to said slots. 60
3. As an article of manufacture a unitary card holder formed from a blank of sheet metal in which the metal is drawn into channel form to provide a bottom and two side 65

walls of equal height throughout their length with the edges of the side walls approaching one another at intervals to provide narrower slots.

4. As an article of manufacture a card holder formed from a blank of sheet metal in which the metal is drawn into channel form with the side edges of the channels approaching one another at intervals to provide narrower slots and also having the edges 75 contacting contiguous to said slots.

This specification signed this 24th day of June, A. D. 1930.

ROLAND A. FURLONG.
